UNITED STATES PATENT OFFICE.

ELLEN HARRIS OVERTON, OF FRANKFORT, KENTUCKY.

FOLDING BOX.

SPECIFICATION forming part of Letters Patent No. 655,939, dated August 14, 1900.

Application filed May 21, 1900. Serial No. 17,415. (No model.)

To all whom it may concern:

Be it known that I, ELLEN HARRIS OVERTON, a citizen of the United States, residing at Frankfort, in the county of Franklin and

5 State of Kentucky, have invented certain new and useful Improvements in Folding Boxes, of which the following is a specification.

My invention relates to what are termed "knockdown" boxes—that is, boxes consisting of sheets or strips so cut and slit that they may be folded up to form a box or box portions and may also be folded down flat; and my invention consists of a knockdown box having two sections, one adapted to enter the other, with means for securing said sections in relatively-different positions, so as to enlarge or decrease the capacity of the box as fully set forth hereinafter and as illustrated in the accompanying drawings, in which—

10 Figure 1 is a perspective view of one of my improved boxes open; Fig. 2, a plan view showing the mode in which the two box-blanks are slit and scored.

The box consists of two sections A B, each 25 made from an oblong sheet or blank of paper or cardboard and each scored along lines *c c*, parallel to each other and to the side edges, and along lines *b b*, parallel to each other and to the ends of the strips or sections. Each

30 section is also slit with a right-angled slit *x*, one portion of which coincides with the line *b* and another portion with the line *c*. As thus scored and cut the portions 2 2 of each blank may be turned up on the line *c* to form the sides of one section of the box, and the portions 7 7 may be turned inward to form the end, and the portion 6 may be folded up against the outside of the portions 7 7, and the portion 5 may be folded over, forming a 35 cover, the portions 4 4, being bent inward, forming side flaps of the top lying against the upturned portions 2 2 on the outside thereof. By this means there is formed two box-sections, each of which has sides and one end 40 and is open at the other end, and the open end of one section is adapted to enter the open end of the other section, as shown in Fig. 1. By moving one section farther into or out of the other section the length of the

45 box may be increased or decreased and suitable means may be employed for connecting the two sections together when they are prop-

erly adjusted. After being thus secured the top may be turned down, first from one section and then the other, thus forming a complete cover and closing the box.

55 While different means may be employed for connecting the two sections together, I prefer to form a plurality of tongues and slots upon the respective sections adapted to engage each other with the said sections in different relative positions.

60 There may be any suitable number of tongues *a* formed by cutting the sides with U-shaped cuts, as shown, and there may be a plurality of tongues on each side 2 and a single slot *d* in the corresponding side of the other section, or there may be one tongue on each side 2 and a plurality of slots *d* in the other section, as shown.

65 Whatever may be the arrangement the end of the section B may be placed in that of the section A in any desired position and the tongues of one section inserted in the slits of the other, so as to secure the same in place.

70 The inturned ends 7 may be secured to the section 6 by providing these ends with slots *g* and the section 6 with tongues *i*, adapted to enter the same, or the tongues may be upon the section 7 and the slots in the section 6.

75 In order to hold down the cover portion, each of the side flaps 4 4 of the cover part 5 may have a tongue *e*, adapted to enter a slit *y* in one of the sides 2.

80 Without limiting myself to the precise construction and arrangement of parts shown, I claim as my invention—

1. A knockdown box consisting of two sections slidable one upon the other, each with two sides a bottom and one open end, and a foldable bottom extension constituting an end and a cover, and means for connecting the sections together in different relative positions, substantially as set forth.

90 2. A knockdown box consisting of two knockdown sections having open ends one fitting in the other, and with tongues and slits whereby the two may be secured together in different positions, substantially as set forth.

95 3. A knockdown box consisting of two knockdown sections having open ends one fitting in the other, and with tongues and

slits arranged to engage with the sections in different relative positions, substantially as set forth.

4. A knockdown box consisting of two knockdown sections having open ends one fitting in the other, and with tongues on one and a plurality of slits in the other whereby to secure the two together in different positions, substantially as set forth.

10 5. The combination in an extensible box, of two sections each with sides and one end and open at the other end, tongues on one section and slits in the other arranged to engage with the sections in different relative positions, substantially as set forth.

15 6. The combination in an extensible box, of two sections slideable one upon the other and each having a bottom and two sides and flaps on the sides at one end for turning inward to close one end of the section, and an extension of the bottom portion having a section adapted to be bent upward against the said flaps, and a further section foldable to form a cover with tongues and slits for connecting the bent-up section with the flaps, and means for connecting the sections together, substantially as set forth.

20 7. The combination in an extensible box, of two sections slideable one upon the other and each having a bottom and two sides and flaps on the sides at one end for turning inward to close one end of the section, an ex-

25 tension of the bottom portion having a section adapted to be bent upward against the said flaps, with tongues and slits for connecting the bent-up section with the flaps, and a terminal section of the bottom extension having side flaps and foldable to form a cover, and means for connecting the sections together in different relative positions, substantially as set forth.

30 8. The combination in an extensible box, of two sections slideable one upon the other and each having a bottom and two sides and flaps on the sides at one end for turning inward, to close one end of the section, an extension of the bottom portion having a section adapted to be bent upward against the said flaps, with tongues and slits for connecting the bent-up section with the flaps, and a 35 terminal section of the bottom extension foldable to form a cover and having side flaps, each with a tongue adapted to a slit in one of the sides of the box, and means for connecting the two sections together, substantially as set forth.

35 In testimony whereof I have signed my name to this specification in the presence of two subscribing witnesses.

ELLEN HARRIS OVERTON.
